UNITED STATES PATENT OFFICE.

SAMUEL H. GIBSON, OF CLEVELAND, OHIO, ASSIGNOR TO THE FANNER MANUFACTURING COMPANY, OF CLEVELAND, OHIO, A CORPORATION OF OHIO.

SADIIRON-HOLDER.

1,376,197.

Specification of Letters Patent. Patented Apr. 26, 1921.

Application filed June 7, 1919. Serial No. 302,555.

To all whom it may concern:

Be it known that I, SAMUEL H. GIBSON, a citizen of the United States, residing at Cleveland, in the county of Cuyahoga and 5 State of Ohio, have invented a certain new and useful Improvement in Sadiron-Holders (C.) of which the following is a full, clear, and exact description.

The present invention relates to a sad 10 iron holder of the type which is particularly designed for use in connection with sad irons which in the trade are known as Mrs. Potts' sad irons.

The object of the invention is to provide 15 a sad iron holder of the type mentioned in which the hand engaging portion is formed of resilient material so that under the action of ironing a certain resiliency and cushioning effect is provided.

20 A further object is to provide a construction such that the hand engaging portion, together with the uprights which support the hand engaging portion with respect to the base and the latch for the holder are 25 formed from a continuous piece of wire which is bent into suitable shape to provide the desired construction.

Further objects of the invention will appear more at large as the description proceeds, and generally speaking it may be said 30 that the invention comprises the elements and combinations thereof set forth in the accompanying claims.

Reference should be had to the accompanying drawings forming a part of this 35 specification in which Figure 1 is a side elevation of a holder embodying my invention; Fig. 2 is a top plan view with the hand engaging portion removed; Fig. 3 is a section 40 upon the line 3-3 of Fig. 1; Fig. 4 is a section upon the line 4-4 of Fig. 1.

Referring to the drawings, 1 indicates the base which at its opposite ends is formed with upstanding portions 2 and 3; portion 45 2 being provided with a suitable opening 2^a and the part 3 being provided with a slot 3^a.

The base is formed with an open portion 4 to provide lightness in construction and is also provided with an open portion 5. Ex-50 tending across the open portion 5 is a bridge member 6, which forms a support for the latch later to be described. Portion 6 has a downwardly extending portion 6^a which

forms a member which in coöperation with the latch engages and holds the sad iron 55 when the handle is affixed to the sad iron.

The hand engaging portion is generally represented at 7 and comprises a wire coil which preferably is of greater diameter at the center portion thereof and tapers toward the ends. The hand engaging portion 7 is supported with respect to the base by two upright members 7^a and 7^b. The hand engaging portion 7 together with the members 7^a and 7^b are preferably formed from 60 a single piece of wire which is fabricated to form the coiled portion for the hand engaging portion as well as the uprights 7^a and 7^b. The upright 7^b extends through 65 slot 3^a and has a portion indicated at 7^c 70 which forms a latch member. This member 7^c bears against the transversely extending member 6 of the base under normal conditions and a continuation of the wire is formed with a loop such as indicated at 7^d 75 and also an extending foot 7^e which extends through the opening 5 in the base and in position to coöperate with the part 6^a of the base.

The wire out of which the construction 80 just described is formed may be of any desired quality and preferably is sufficiently flexible so that by the inherent resiliency of the wire the latch member 7^c is normally held against the cross member 6 of the base.

The part 7^d takes the place of the usual 85 knob and is adapted to be engaged by a finger of the user so that it may be raised against the resiliency of the wire to permit its being adapted to a sad iron.

The portion 7^b of the wire extends 90 through the slot 3^a in the base but is not secured therein so that it may have a limited amount of movement. This is desirable inasmuch as it permits the transfer of the strain incident to raising the knob portion 7^d of the wire through the coils of the hand engaging portion so that the movement required for flexibility is not confined to the latch portion 7^c but is transmitted to the 95 coils of the hand engaging portion. This construction is important inasmuch as it renders the wire less liable to breakage than would be the case if the entire resiliency incident to returning the latch to its 100 normal position were provided in the por-

tion 7°, because under the sharp bending action of such a construction the wire would be liable to crystallize and break.

The construction as described is exceedingly simple and is capable of being fabricated by simple manufacturing methods which result in the low cost of production.

Having described my invention, I claim—

1. A sad iron holder comprising a base member, upright members mounted adjacent the ends of the base, a connecting handle member between the upright members, a latch having a knob and a foot, which are formed from a continuous piece of resilient material, which material is an extension of one of the end upright members.
2. A sad iron holder comprising a base member, an upright member mounted adjacent one end of the base, a handle member secured at one end of said upright member, a second upright member secured to the opposite end of the handle, said upright member being formed of a continuous piece of material extending through an opening 25 in the base and bent to a position substan-

tially parallel with said base, said continuous piece of material having formed thereon a knob and a foot portion.

3. A sad iron holder comprising a base member and hand engaging portion formed as a wire coil, means for supporting one end of the wire coil on the base, an upright formed as a continuation of the coil of the hand engaging portion and extending through an opening in the base and a latch 35 forming a continuation of the said wire, said latch being provided with a folded portion and with a foot.

4. A sad iron holder comprising a base member and a continuous wire secured at 40 one end to the base portion and formed as an upright and as a coiled hand engaging portion and as a second upright, said second upright portion extending through an opening in the base, the said wire also forming a latch member having a fold therein and an extending foot.

In testimony whereof, I hereunto affix my signature.

SAMUEL H. GIBSON.
